US0D1024342S

(12) **United States Design Patent** (10) **Patent No.:** **US D1,024,342 S**
(45) **Date of Patent:** **** Apr. 23, 2024**

(54) **NEUROMODULATION DEVICE**

(71) **Applicant:** **SORANUS ARGE VE
DANISMANLIK HİZMETLERİ
SANAYI TİCARET A.Ş., Izmir (TR)**

(72) **Inventors:** **Ahmet Özgür Yeniel, Izmir (TR);
Özgün Selim Germiyan, Izmir (TR);
Serdal Temel, Izmir (TR); İlker
Başaran, Izmir (TR); Gökhan
Bulunur, Izmir (TR); Ahmet Mete
Ergenoğlu, Izmir (TR)**

(73) **Assignee:** **SORANUS ARGE VE
DANISMANLIK HİZMETLERİ
SANAYI TİCARET A.Ş., Izmir (TR)**

(**) **Term:** **15 Years**

(21) **Appl. No.:** **29/823,717**

(22) **Filed:** **Jan. 19, 2022**

(30) **Foreign Application Priority Data**

(57) **CLAIM**

The ornamental design for a neuromodulation device, as shown and described.

DESCRIPTION

FIG. 1 is a perspective view of an embodiment of a neuromodulation device showing our new design;

FIG. 2 is a front elevational view thereof;

FIG. 3 is a rear elevational view thereof;

FIG. 4 is a right side elevational view thereof; and,

FIG. 5 is a top plan view thereof.

The broken lines shown in the drawings are included for the purpose of illustrating portions of the neuromodulation device and form no part of the claimed design.

1 Claim, 5 Drawing Sheets
